UNITED STATES PATENT OFFICE.

JAMES GRAY, OF TRENTON, NEW JERSEY.

SELF-LEVELING LAVATORY-ASSEMBLING MACHINE.

Application filed August 16, 1927. Serial No. 213,237.

This invention relates to assembling machines, and more particularly to self-leveling lavatory assembling machines.

The lavatories and pedestals are made separately and as the lavatories are usually warped a little as they come from the kilns, care has to be taken to level each lavatory with respect to the corresponding pedestal to assure proper final assembly thereof. Preferably such leveling is effected by forming a seat of plastic material such as plaster Paris on each lavatory before shipping from the factory so that when the lavatory and pedestal are finally assembled in position for use, the lavatory will be in proper leveled position on the pedestal. The seat on each lavatory is formed by placing the lavatory and the corresponding pedestal in proper relative position, filling the space between them with the plastic material and after permitting the plastic material to set, removing the pedestal from the seat thus formed. The lavatory and pedestal are then transported or shipped as separate parts ready for assembling. So far as I am aware, the work of forming such seats on the lavatory has heretofore been done entirely by hand.

The main object of my invention is to provide a machine whereby pedestals and lavatories or bowl portions may be readily positioned for the formation of such seats of plastic material and with a saving of labor.

A further object of the invention is to provide means whereby the height of each assembled lavatory and pedestal may be definitely determined.

According to the preferred embodiment of my invention, I provide means whereby the pedestal may be held in inverted position against a downwardly facing abutment which preferably is adjustable vertically. The means for supporting the pedestal against the abutment above the same is rendered effective by counterbalance or other suitable means and is arranged for release to enable insertion and removal of the pedestal. The lavatory is placed in the apparatus in inverted position and by suitable means is raised into engagement with adjustable leveling devices which determine its position with relation to the pedestal held in the apparatus. By use of suitable latching means, the lavatory is held in its level position while a seat of plastic material to re-

ceive the upper end of the pedestal is formed on the bottom of the lavatory and allowed to set. The pedestal and lavatory are then removed from the machine and shipped separately. The seats formed in this manner assure proper final assembly of the parts.

Other objects and advantages will be pointed out hereinafter or will be apparent from consideration of the accompanying drawings. It is to be understood that these drawings are to be considered in an illustrative rather than in a limiting sense.

In the drawings,

Fig. 1 is a front elevation of the machine; Fig. 2 is a side elevation of the machine; and

Fig. 3 is a top plan view with certain parts omitted.

In the construction illustrated, there is an angle iron frame provided with an adjusting screw 1, to determine the vertical position of a pedestal 2, the screw being threaded in a collar 3 secured to a plate in the upper part of the frame. At its lower end, the screw 1 has fixed thereto a collar 4 having at its lower edge a flange which is utilized to support a plate 5 which serves as an abutment against which the base of the inverted pedestal is held. The plate 5 is supported from the flange of the collar 4 by means of suitable brackets secured to the plate 5 and engaging the top of the flange while permitting rotation of the collar 4 without rotation of the plate 5. This arrangement facilitates vertical adjustment of pedestals while held in engagement with plate 5 and without turning the plate 5. The foot of each pedestal is usually about 12 inches square and the plate 5 must be not less than 14 inches and might therefore interfere with the cables 9 if turned.

The pedestal 2 is centered with respect to the screw 1 and supported against the plate 5 by means of frames including arms 6 arranged in pairs and pivoted at opposite sides of the frame. At their inner ends these arms support shafts or rods 7 on which are mounted balls 8 of suitable material, such as hard rubber, to engage the pedestal without marring the surface thereof. The arms 6 are urged upwardly into effective position to properly locate and support the inverted pedestal 2 by means of cables 9, preferably of wire, connected at one end with the frames including the arms 6 and passing over pul-

leys 10 and 11 at the top of the frame and downwardly at the outside of the frame where they are connected with a bar 12 carrying counterweights 13 and suitably guided on the frame. In order to cause the arms 6 to swing downwardly to permit insertion or removal of one of the inverted pedestals 2, there is provided an arrangement including cables 14 connected with the bar 12 and extending upwardly to pulleys 15 and around the same to the front of the machine where they pass around pulleys 16 and downwardly to a treadle 17 to which they are connected. When it is desired to have the arms 6 swing downwardly, the operator steps on the treadle 17 and raises the counterweights.

After the pedestal 2 has been placed in the apparatus, the lavatory 15 in inverted position is brought into proper position relative 20 to the pedestal. This is effected by placing the lavatory on cross bars 18 supported by and balanced on a central cross bar 19, and lifting the lavatory by means which include levers 20 at opposite sides of the frame to 25 which the levers are pivoted intermediate of their ends, and rods 21 connected at their upper ends with said levers and at their lower ends with said bar 19 by means including springs 22 interposed between the 30 lower face of the beam or bar 19 and suitable stops on the rods 21. At their outer ends the levers 20 are provided with pivoted pawls 23 adapted to engage teeth in racks 24 fixed on the frame and to hold the levers 25 35 20 in a position to support the lavatory 15 in leveled position against stops 25 in the form of screws threaded in brackets 26 supported in slots in fixed brackets 27 on the frame. The stops 25 may be adjusted in 40 proper leveling position by use of a level and the springs 22 may be compressed to the desired degree as determined by the extent to which the outward ends of the levers 20 are depressed.

45 Preferably the machine is operated in the following manner:

The operator steps on the treadle 17 and raises the counterweights 13, thereby permitting the arms 6 to swing downwardly. A 50 pedestal 2 in inverted position is then inserted with its base adjacent the plate 5 and the treadle is released. The counterweights 13 then cause the arms 6 to be swung upwardly and the balls 8 engage the pedestal 56 on opposite sides and press it upwardly against the plate 5. Usually the pedestals are substantially square in cross section. A 60 lavatory 15 is then placed in inverted position on the crossbars 18 and the operator forces down the outer ends of levers 20 until the four corners of the lavatory engage the 65 already been leveled.

When the first pedestal and lavatory have 70 been inserted, the vertical position of the

pedestal is adjusted by means of the screw 1 to give the desired space for the plastic material or plaster Paris between the pedestal and lavatory. After this adjustment has been made for the first lavatory and pedestal, 75 no further adjustment need be made unless there is too great a variation in the pedestals and lavatories.

After the plastic material has been inserted between a pedestal and lavatory and allowed to set, the levers 20 are swung downwardly sufficiently to release the pawls 23 and are then permitted to swing in the opposite direction to lower the lavatory and permit the removal thereof. The pedestal 80 17 may be released by stepping on the treadle 17 and may then be removed from the machine.

As will be evident from the scope of the 85 appended claims, various changes in the details of construction may be made without departing from the spirit of my invention.

Having thus described my invention, what I claim as new and desire to secure by Letters Patent is:

1. In a machine for preparing parts for assembly, an abutment to determine the position of one of the parts to be assembled, means to engage and hold such part in position against the abutment and means for positioning a second part relative to the first including means for limiting movement of the second part relative to the first for positioning it properly with respect to the first part.

2. In a machine for preparing lavatories and pedestals for assembly, a downwardly facing abutment, means for supporting an inverted pedestal with its base against said abutment, means for raising an inverted lavatory to position for assembly with the pedestal, and means for limiting such movement of the lavatory and positioning it with respect to the pedestal.

3. In a machine for preparing lavatories and pedestals for assembly, a downwardly facing abutment, means for supporting an inverted pedestal with its base against said abutment, means for lifting an inverted lavatory for assembly with said pedestal, lavatory positioning means engaged by the lavatory when lifted by said lifting means, and means for adjusting the height of said abutment.

4. In a machine for preparing lavatories and pedestals for assembly, downwardly facing abutment means to be engaged by the base of an inverted pedestal, pivoted devices for engaging said pedestal and holding it against said abutment means, counterbalancing means for rendering said engaging devices effective, means for positioning a lavatory properly for assembly with a pedestal in the machine, and means for swinging said pivoted devices to ineffective posi-

tion to permit insertion of a pedestal into the machine or removal of an assembled pedestal and lavatory.

5. In a machine for preparing lavatories and pedestals for assembly, releasable means for holding a pedestal in inverted position, adjustable means for positioning an inverted lavatory with respect to said pedestal when raised toward the same, and lavatory lifting means adapted to permit adjustment of the lavatory with respect to said positioning means when moved thereagainst.

6. In a machine for preparing lavatories and pedestals for assembly, releasable means for holding a pedestal in inverted position, adjustable means for positioning an inverted lavatory with respect to said pedestal when raised toward the same, and lavatory lifting means including a part to engage the lavatory, a central cross bar on which said part is balanced, and means connected with the opposite ends of said cross bar for lifting the same.

7. In a machine for preparing lavatories and pedestals for assembly, releasable means for holding a pedestal in inverted position, adjustable means for positioning an inverted lavatory with respect to said pedestal when raised toward the same, lavatory lifting means including a part to engage the lavatory, a central cross bar on which said part is balanced, and means connected with the opposite ends of said cross bar for lifting the same, including levers and yieldable connections between the levers and the ends of said cross bar.

8. In a self leveling lavatory machine, an abutment to determine the position of one of the parts to be assembled, means including a screw means for adjusting the position of the abutment, means to engage and hold such part in position against the abutment and means for positioning a second part relative to the first, including means for

limiting movement of the second part relative to the first and positioning it properly with respect to the first part.

9. In a self leveling lavatory machine, a downwardly facing abutment, means for supporting an inverted pedestal with its base against said abutment, means for raising an inverted lavatory in position for assembly with the pedestal, and adjustable means for positioning the lavatory with respect to the pedestal, including a plurality of screws to be engaged by said lavatory.

10. In a machine for assembling lavatories and pedestals, downwardly facing abutment means to be engaged by the base of an inverted pedestal, devices for engaging said pedestal near its base, and holding it against said abutment means, yieldable means for rendering said engaging devices effective, means for positioning a lavatory properly for assembly with a pedestal in the machine, and means for moving said devices to ineffective position to permit insertion of a pedestal into the machine or removal of an assembled pedestal and lavatory.

11. In a self leveling lavatory machine for assembling lavatories and pedestals, releasable means for holding a pedestal in inverted position, adjustable means for positioning an inverted lavatory with respect to said pedestal when raised toward the same, lavatory supporting means including a part to engage the lavatory, a cross bar on which said part is balanced and lifting means so connected with said part at opposite sides of the machine as to permit rocking of said part, and including levers and yieldable connections between the levers and the ends of said cross bar.

Signed at Trenton, in the county of Mercer and State of New Jersey, this 11th day of August, A. D. 1927.

JAMES GRAY.
